Patented Dec. 3, 1974

233,824

ELECTRIC FENCE INSULATOR

Albert T. Berg, Jr., and Howard Langlie,
both of Ellendale, Minn. 56026

Filed July 31, 1972, Ser. No. 276,552

Term of patent 14 years

Int. Cl. D13—03

U.S. Cl. D8—230

Fig. 1

Fig. 2

Fig. 3

Fig. 4

Fig. 5

Fig. 6

FIG. 1 is a perspective view of an electric fence insulator embodying our new design;

FIG. 2 is a front elevational view thereof;

FIG. 3 is a side elevational view taken from the right in FIGS. 1 and 2;

FIG. 4 is a rear elevational view thereof;

FIG. 5 is a top plan view thereof; and

FIG. 6 is a bottom plan view thereof.

We claim:

The ornamental design for an electric fence insulator, substantially as shown.
